Samuel Morrison, Northumberland, Pa.

Letters Patent.

The subject matter referred to in these Letters Patent and making making part of the same containing a description in the words of the said Samuel Morrison himself of his improvement in the breech, for discharging one or two loads from one barrel.

To all to whom these presents shall come: Be it known that I, Samuel Morrison, of Milton in the County of Northumberland and State of Pennsylvania have invented a new and useful improvement in breech locks, and in the mode of applying them so as to discharge either one or two loads from a single barrel at one and the same time, and that the following is a full and exact description of the construction and operation of said invention as invented or improved by me. The invention or improvement consists of a lengthened breech pin (A. B. fig. 3a) a lever (fig. 4) a dog (fig. 8d) a main spring (A. B. fig. 52) a set dog (fig. 53) and a trigger (fig. 6) for the purpose of regulating the force of the main spring and a wire connecting these in such manner with the breech pin and with each other, that when the trigger is pulled one or two loads may be discharged from a single barrel at one time without the necessity of discharging either two loads or two locks. — The breech pin (A. B. fig. 3a) is made about the width of the barrel, and for a common gun from two and a half to three inches along the length of the gun. Near the right side of the breech pin a hole (fig. 6a) is made for the admission of the lever which is secured thereto by a wire and a screw and a pivot (7b. fig. 32) so that when the lever is raised or cocked the nose of the dog (8) is pressed into the notch (11) of the lever by the action of the main spring, and then secured to the lever until by pulling the trigger the nose of the dog is disengaged, and allows the lever to be thrown by the force of the

main

Mainspring (A.B) upon the percussion gunpowder cap and thus causes the explosion or discharge. The mainspring is fastened by a screw (fig 8) upon the underside of the brith-piv, and in such a manner as to be sufficiently firm upon the dog (fig 3.C) to throw it more into the notch (5) of the lever where the latter is raised or rocked. The dog works upon the underside of the brith-piv upon a pivot (P). The screw (8) is for the purpose of regulating the rising of the dog, and this enables the gunner to shoot with a light or strong finger as occasion may require. The mainspring is also secured by a pivot (Q) in the underside of the brith-piv, and by turning the brage-screw (6) which passes upon it at (P) its force or strength is increased or diminished at the pleasure of the gunner.

The brith-piv is set into the brith of the gun and secured by two screws (10 of fig 9) passing through the same into the side of the brith so that when a gun is finished and ready for use the mainspring, dog and mainspring are enclosed within the brith, and of course nothing belonging to the lock itself is visible but the upper surface of the brith-piv, the heads of the set and gauge screws and the lever. Upon the upper side of the lever there is a projection (fig 11) forming part of the snout, and designed as a means of raising or rocking it. And a little in advance of the fore part (10) the lever is made in the shape of an inverted bowl, which falls upon the cap and at the time of its explosion prevents the fragments from injuring the gunner. The tube in which the cap is placed is secured into a shoulder (9 of fig 5) formed upon the right hand side of the barrel so that it can be removed at pleasure for the admission of another to be calculated for the percussion gunpowder. Through the bowl of the lever there is also a hole made for the introduction of either a screw with a pivot for the explosion of percussion gunpowder or one for the explosion of caps, so that either can be used at the will of the gunner. The invention or improvement further consists in constituting the lever and a second tier.

and in placing them in such a manner as to shoot off either one or two loads from a single barrel at one time - the barrel calculated for those purposes has the diameter of the bore for the first charge, made smaller than the diameter for the second and the rest of the barrel. The length of the bore for the first charge must be of a size proportionate to that of the gun, and near the shoulder on the tube I fig 37, in which the gun grain powder is placed for igniting the second charge is placed sufficiently in advance of the shoulder and tube to have its touch hole opening upon the second charge a little more than the diameter of the large bore, from the shoulder which the smaller one meets at its place of connection with the large bore.

The two bores are also the place for a bullet belonging to the first charge is represented by the dotted lines on the bore of fig 37. The bore for a gun calculated for shooting two loads has two bowls (A, B, C figure 38) the one sufficiently in advance of the other to suit the relative situation of the tubes. And in order at any time to shoot off either one or both loads at once, one of the bowls is made with a revolving block (A, D) connecting through the top of the bowls with a thumb-piece (D) so that when placed as is prescribed in the figure both loads are discharged at once, but when the block is turned half round by the thumb-piece so that the part D takes the place now occupied by the part B and does not touch the tube, the forward load only is discharged because when the block is in this last position situation the forward bowl is not prevented by the block from revolving full upon the forward tube. The revolving block may be put into either the forward or hindmost bowl of the bore and the bore may be made without the movable pieces through the bowls, if only one kind of spinning is to be used. That I claim as my own invention and not previously known or used in the above described machine are first extending the barrel past the gun-

Converting it into a lock plate - second making the lever upon the principle described above with either one or two bowls with the moveable points or screws - Third, the revolving block, and the mode of fixing it in the bowl which enables the gunner to use either paracession gun powder or caps, and to discharge either one or both loads at a time with but the one lever. Fourth, making the lever to turn inward on the bracket piece, which prevents any jiving or jerking off from the fall of the lever immediately before the explosion - Fifth, the ordinary gauge screws (226 fig 318) are used for the purposes already described. Sixth, the shoulder or shoulders formed in barrels, into which the tubes for either paracession gun powder or caps, may be inserted at the will of the gunner.
